[57] CLAIM

The ornamental design for an electric crepe pan, as shown and described.

DESCRIPTION

FIG. 1 is a side elevational view of an electric crepe pan showing my new design, the side opposite being a mirror image thereof;

FIG. 2 is a top plan view of the design;

FIG. 3 is a bottom plan view of the design;

FIG. 4 is a front elevational view of the design; and

FIG. 5 is a rear elevational view of the design.
